UNITED STATES PATENT OFFICE.

MORRIS C. ROMER, OF BROOKLYN, NEW YORK.

LOCK JOINT FOR CONTAINERS AND METHOD OF PRODUCING THE SAME.

Application filed May 5, 1926. Serial No. 106,896.

This invention relates to a lock joint for containers and a method of producing the same, the invention being particularly applicable to containers made from multiple 5 ply material, such as reinforced corrugated board or the like.

Heretofore containers or cartons constructed of materials of this character have been closed and sealed by gummed tape, 10 which presents certain objectionable features and disadvantages in that it does not produce a positive and effectual seal and admits of spurious opening and resealing of the carton without detection.

15 The present invention comprehends a lock joint and method of producing the same for establishing a strong and effectual connection between the meeting edges of sections of materials, which when used in connection with a binding means positively precludes unauthorized opening and resealing without detection.

20 More specifically the invention comprehends a lock joint for connecting the meeting edges of sections of material having at least three plies, which comprises portions of the outer plies of each section extending beyond the intermediate ply or plies, in which said portions are scored, bent and 25 interengaged to provide a flush locking connection, and with which means is employed for binding and sealing said portions in interengaged or locked relation.

The invention furthermore comprehends 30 a lock joint and method of producing the same, which are simple, inexpensive and efficient.

With the above recited and other objects in view, reference is had to the following 35 specification and accompanying drawings in which there is exhibited one example or embodiment of the invention which is in no way intended as a limitation upon the scope of the appended claims as it is to be clearly 40 understood that variations and modifications 45 which properly fall within the scope of said claims may be resorted to when found expedient.

In the drawings—

50 Figure 1 is a sectional perspective view illustrating sections of the material in juxtaposition prior to interengagement thereof;

Fig. 2 is a similar view illustrating the meeting edges of the sections interengaged 55 or locked;

Fig. 3 is a perspective view of a carton

or container closed by means of the joint embodying the invention;

Fig. 4 is a sectional view illustrating a joint arranged adjacent the corner of a 60 carton;

Fig. 5 is a perspective view of a carton 65 illustrating a joint bound by means of a metal binding strip, the ends of which are sealed;

Fig. 6 is a sectional perspective view taken approximately on the line 6—6 of Fig. 5;

Fig. 7 is a fragmentary perspective view.

Referring to the drawings by characters of reference, 10 and 11 designate two sections of material, the meeting edges of which are to be joined by a lock joint in accordance with the invention. The material must be of three or more plies, including the outer plies 12 and 13, and an intermediate ply 14, which, as illustrated, is a corrugated filler. In utilizing material of this nature as manufactured, the filler or inner ply or plies 14, is routed back from the edges of the outer plies 12 and 13 a 80 sufficient distance to produce extending portions. The extending portions 15 and 16 of the section 10 are scored at 17 and 18 at a point substantially intermediate their length to provide bendable terminals 19 and 20, which are bent outwardly and rearwardly. The extending portions 21 and 22 of the section 11 are scored intermediate their length at 23 and 24 to provide bendable 85 terminals 25 and 26, which are designed to be bent inwardly and rearwardly.

The extending portions 15 and 16 are squeezed together as illustrated in Fig. 2, so that their confronting faces are in contact and the terminals 25 and 26 are interengaged between the terminals 19 and 20 and the extending portions 15 and 16 which obviously positions the terminals 19 and 20 between the terminals 25 and 26 and the extending portions 21 and 22 of the section 11. This arrangement 100 obviously produces a lock joint in which the free edges of the terminals 19 and 20 engage within the bights formed by the rearward bending of the terminals 25 and 26 along the score lines 23 and 24, and likewise engage the free edges of the terminals 25 and 26 within the bights formed by the bending of the terminals 19 and 20 along the score lines 17 and 18. In order to prevent 105 relative outward swinging movements of the interengaged portions, a suitable binding means may be employed, such as glue or

- any other suitable adhesive, which is preferably applied between the confronting faces of the terminal 25 and the extending portion 15 and the confronting faces of the terminal 25 and the extending portion 16. In lieu of an adhesive, a metal binding strip 27 may be passed or threaded between the terminal 19 and the extending portion 21, the exposed end portions of the binding strip being secured by a suitable seal 28. In lieu of either an adhesive or a metal binding strip, stitching may be used to secure the interlocked joined portions together. This is a distinct advantage in that heretofore stitching of corrugated containers was impracticable due to the fact that the corrugated inner ply or filler would of necessity collapse, whereas with the present form of joint the stitching will extend through solid plies or layers only.
- Fig. 3 illustrates the lock joints at A and B secured by an adhesive to form the carton C. Fig. 4 illustrates the lock joint D forming the body of the carton produced adjacent a corner thereof. Fig. 5 illustrates a completed carton having lock joints between the meeting edges of the end flaps F, bound by means of a metal binding strip and sealed.
- The method of connecting the meeting edges of sections of a three-ply material essentially consists in either removing a portion of the intermediate ply of each section adjacent the free edges of the outer plies or otherwise forming the meeting edges with portions of the outer plies pro-

jecting beyond the intermediate ply or plies, then scoring, bending and interengaging the extending portions of the outer plies to provide a lock joint therebetween. The method may further include the step of binding said interengaged portions against separation adhesively by stitching or by means of a metal binding strip threaded through the interengaged portions with the ends joined by a seal.

What is claimed is:

1. A lock joint for connecting the meeting edges of sections of a three-ply material, comprising portions of the outer plies of each section extending beyond the intermediate ply, said portions being scored, bent and interengaged to provide a locking connection.
2. A lock joint for connecting the meeting edges of sections of a three-ply material, comprising portions of the outer plies of each section extending beyond the intermediate ply, said portions being scored, bent and interengaged to provide a locking connection, and means for binding said portions in interengaged relation.
3. A lock joint for connecting the meeting edges of sections of a three-ply material, comprising portions of the outer plies of each section extending beyond the intermediate ply, said portions being scored, bent and interengaged to provide a locking connection, and adhesive means for binding said portions in interengaged relation.

MORRIS C. ROMER.
